CATALYTIC DESULFURIZATION OF
PETROLEUM HYDROCARBONS

Percy Meyer, London, England, assignor to Anglo-Iranian Oil Company Limited, London, England, a British joint-stock corporation

Application April 12, 1949, Serial No. 87,068
In Great Britain April 19, 1948

12 Claims. (Cl. 196—28)

1

This invention relates to the catalytic desulphurisation of petroleum hydrocarbons.

In the specifications of co-pending applications Nos. 35,976, Patent No. 2,573,726; 46,502, Patent No. 2,574,445, and 68,416, Patent No. 2,574,446, there is described a process for the hydrocatalytic desulphurization of naphthene-containing petroleum fractions which is carried out by means of hydrogen derived solely from the fractions during the course of the process. The fractions are passed in vapor form over a sulphur-resistant dehydrogenation-hydrogenation catalyst, preferably one comprising the oxides of cobalt and molybdenum deposited on a support, at a selected temperature within the range approximately 650—800° F. and at a selected pressure within the range approximately 25—500 lb./sq. in., whereby an amount of hydrogen is obtained by dehydrogenation of naphthenes contained in the fractions not substantially greater than that required to convert organically combined sulphur in the fractions into hydrogen sulphide and to maintain by hydrogen recycle the pressure in the reaction zone. Such a process may conveniently be referred to as an "autofining" process.

In carrying out such processes, it has been the practice to recover a desired fraction from the crude oil by conventional methods and then to subject the fraction to the autofining process for the reduction of its sulphur content. Such a method of operation thus involves the preliminary separation of the desired fraction which has to be re-vaporised when subjected to the autofining process. Furthermore, the autofining process can only be effectively carried out on fractions which contain a sufficient proportion of naphthenes to generate sufficient hydrogen to maintain the vapour phase. To some extent, the deficiency of naphthenes in a specific fraction may be remedied by blending the fraction with another fraction which is richer in naphthenes, but the scope of this expedient is limited by the characteristics of the available fractions. Yet again, the autofining process can only be effectively applied to fractions which are capable of being recovered from the crude oil without deleterious effect on their desirable properties. Thus, it is difficult to separate the wax and lubricating oil fractions from the crude oil by distillation without thermal decomposition or cracking, but it is, nevertheless, highly desirable to provide a method of desulphurising such fractions.

It is among the objects of the present invention

to provide a continuous process for the catalytic desulphurisation of petroleum fractions derived from crude oil, or of mixtures of crude oil distillates and residues, in which the boiling range of the fractions subjected to desulphurisation may be controlled within very wide limits. It is another object of the invention to enable the autofining process to be applied to the selected fraction without the necessity of previously isolating the fraction from the crude other than in the course of the process. Yet another object of the invention is to enable fractions which are with difficulty volatilised to be isolated from crude oil and subjected to the autofining process in a continuous process under conditions in which there is no cracking or thermal decomposition of the fractions.

According to the invention, a process for the catalytic desulphurisation of petroleum fractions comprises passing a crude oil or a mixture of crude oil distillates or residues to a primary distillation column, passing the overhead product from said column to an autofining zone, passing the products from the autofining zone to a distillation column for the separation of the hydrogen and hydrogen sulphide as overhead product, and the recovery of one or more desulphurised fractions, and passing some or all of said hydrogen-containing gaseous fraction and, if desired, any or all of said desulphurised fractions to the base of the primary distillation column to control the degree of vaporisation achieved in said column and thereby to control the boiling range of the fraction submitted to autofining.

According to one method of carrying the invention into effect, the crude oil is first debutanised in a conventional distillation column, and the debutanised crude vaporised and passed to the primary distillation column for the separation overhead of the fraction to be autofined, the degree of distillation in the primary column being controlled by the admission of hydrogen to the base of the column and/or by means of reflux returned to the top of the column. If the fraction submitted to the autofining zone is deficient in naphthenes, such deficiency may be made good by recycling naphthene-containing light hydrocarbon fractions recovered from the products of the autofining operation to the crude oil to be vaporised or to the base of the column in admixture with the hydrogen recycled thereto. If desired, also, such light hydrocarbons may be returned to the top of the primary distillation column as reflux.

According to another method of operation, the crude oil is contacted with asphalt precipitants, such as dissolved hydrogen, methane, ethane, propane and butane, and the de-asphalted crude oil vaporised and passed to the primary distillation column in which the degree of vaporisation is controlled as above described. The de-asphalting process is advantageously carried out under pressure up to 500 lb./sq. in and at temperatures between 0° F. and 200° F., both temperature and pressure being varied according to the nature of the crude oil and the desired boiling range of the fraction to be autofined.

The asphaltic residue recovered from the de-asphalting process may be distilled for the recovery of paraffinic precipitant and the asphalt blended with hydrocarbon fractions recovered from the products of the autofining process for the production of fuel oils. Paraffinic asphalt-precipitant may also be recovered from the products of the autofining reaction and after being separated from the asphalt may be returned to the de-asphalting stage. If desired, some of the paraffinic asphalt-precipitant may be recovered from the liquid de-asphalted mixture prior to the entry of the mixture into the autofining zone.

According to a modification of the last described method of operation the de-asphalted mixture may be treated, as by cooling, by varying the content of hydrogen, of paraffinic or of recycle hydrocarbons, or by varying the temperature and pressure to separate the mixture into a solid phase, comprising mainly wax, and a liquid phase, comprising non-crystallisable liquid fractions. Either the recovered wax, or the residual liquid, may then be passed to the autofining zone.

Two examples of process according to the invention will now be described with reference to Figures 1 and 2 respectively, of the accompanying drawings.

Referring to Figure 1, crude oil enters at 1 and passes to a conventional distillation column 2 equipped with conventional reflux condenser 3, and means for heating the oil. In this column the most volatile fractions of the crude oil, such as air, methane, ethane and light hydrocarbons generally, are distilled off and withdrawn at 4, 5. The residual oil (now free from dissolved gases and from such light hydrocarbons as it is desired or found preferable to remove at this state) is passed into a vaporising furnace 7. Before entering the furnace, hydrogen arising from the process may be injected into the oil at 6; and there may at the same time be injected at this point a recycle stream of light distillate such as will yield sufficient free hydrogen to maintain a more than adequate supply of self-generated hydrogen. Water, if present in the crude oil, may be distilled off in column 2, but water or water vapour if found advantageous to catalyst performance may be injected at 6 and/or at 9. Leaving the furnace 7, the partially vaporised mixture passes to a flash vessel 8, from which vapours are separated overhead at 13, and tar or asphaltic residue is separated at 12. To assist stripping the tar of fractions which are with difficulty volatilised, the flash vessel 8 is fitted with a perforated pipe 11, into which hydrogen, light hydrocarbons, and/or steam, may be passed, these being pre-heated if necessary, to a suitable temperature by heater 10.

The vapours leaving the flash vessel 8, are

controlled as to content of high-boiling components by reflux returned to the top of the flash vessel, and the total vapours at 13 consist of a mixture of:

- 5 (a) Hydrocarbons freshly produced from the in-put crude oil.
(b) A carrier such as hydrogen and/or recycle hydrogen-donating hydrocarbons.

10 Leaving the bottom of vessel 8, as liquid at 12, is a non-vaporised residuum which may range from light fuel oil to asphalt.

From 13, the mixed vapours pass to a furnace 14, in which the temperature is adjusted to suit the desired performance of the catalyst 15. Should the temperature leaving 13 be too high to suit the catalyst, the furnace 14 would not be operated, but the reflux or quench system at the head of vessel 8, the heaters of 7 and 10, and the hydrogen or hydrocarbon recycle rate at 6 and 9 would be adjusted to give the desired temperature.

In passing over the catalyst, part of the freshly distilled and/or recycle hydrocarbons decompose to generate hydrogen which, together with the recycle hydrogen, converts most of the sulphur present in the oil to hydrogen sulphide.

The drawing illustrates a batchwise operation, the catalyst being regenerated at intervals, but it is to be understood that a moving-bed or fluidised catalytic process could be employed.

After leaving the catalyst chambers, the vapour is cooled at 16 and passes to a vapour-liquid separator at 17, from which non-condensed gas consisting mainly of hydrogen is recycled via line 18 and compressor 19 to feed points 6, 9. In the course of operation the process generates excess hydrogen which may conveniently be withdrawn for storage or other disposal, at point 20. The condensed liquid products from 17 are now subjected to conventional distillation at 21, giving overhead gas which may be treated for purification or sulphur recovery (22, 23), compressed (24) and recycled; and giving also hydrocarbon streams such as 25, 26, 27 which may as necessary constitute the desired desulphurised product, or may when required be recycled via 28 to 6, 9, to donate hydrogen, or may be further fractionated or refined, to give finished products.

50 Figure 2 illustrates a process wherein a liquid-phase precipitation of non-volatile asphaltic components is first effected. The crude oil or topped residuum enters at 1 and is contacted in vessel 2 with asphalt precipitants such as dissolved hydrogen, methane, ethane, propane, butane or similar light hydrocarbons entering at 3.

From the bottom of vessel 2, asphaltic residues are discarded via stripper 4, for disposal at 5, the light paraffinic precipitants being distilled-off, and recycled to 3, while the asphalt is blended with oils arising from 12, 25, 26, 27, to give a marketable quality of fuel oil or asphalt.

From the top of vessel 2, the de-asphalted mixture of oil and asphalt-precipitant passes through a heating system, such as a furnace with heat exchangers etc., indicated at 7. Prior to entry to the heating system, hydrogen may be introduced into the light hydrocarbon-oil mixture at 6, to assist vaporisation, or, alternatively, the de-asphalted mixture of oil and asphalt precipitant may first be treated for wax recovery by conventional methods, and either the oily components of the crude oil, or the waxy solid-phase components of the crude oil, mixed

with hydrogen and recycle light hydrocarbons, may be passed via 6, to the desulphurising zone.

The mixture then enters separation vessel 8, fitted with a hydrogen and/or light hydrocarbon recycle pipe 11, a liquid bottoms exit at 12, and a reflux head and vapour exit 13. In this vessel, transition to the vapour state occurs and any heavy fractions which are not required to pass over the desulphurisation catalyst are condensed to liquid and discharged via 12 to fuel oil blending, or otherwise removed from the system.

The issuing vapours now pass to furnace or heater 14, in which the temperature is adjusted to suit the desired performance of the catalyst 15. Should the temperature leaving 13 be too high to suit the catalyst, the furnace 14 would not be operated, but the reflux or quench system at the head of vessel 8 and the hydrogen or hydrocarbon recycle rate at 3, 6, and 9, would be adjusted to give the desired temperature.

I claim:

1. A continuous process for the hydrocatalytic desulphurization of petroleum hydrocarbons, which comprises the steps of: passing a naphthalene-containing feedstock selected from the class consisting of crude oil, and mixtures of crude oil distillates and residues to a primary distillation column; recovering as an overhead product of said column a vapor mixture of normally gaseous and normally liquid components including a content of hydrogen-donating naphthalenes recovered in a later step of the process and recycled to said column; passing said overhead product to an autofining zone wherein said overhead product is contacted with a sulphur-resistant hydrogenation-dehydrogenation catalyst at a selected temperature within the range 650-800° F. and at a selected pressure within the range 25-500 lb./sq. in., whereby an amount of hydrogen is produced by dehydrogenation of naphthalenes contained in said overhead product not substantially in excess of that required to convert organically combined sulphur contained in said overhead product into hydrogen sulphide and to maintain said pressure in said autofining zone; separating the products from said autofining zone into a gaseous fraction comprising hydrogen and hydrogen sulphide, and at least one normally liquid desulphurized fraction; controlling the degree of vaporization achieved in said distillation column and thereby the boiling range of said overhead product and simultaneously correcting any deficiency in the content of hydrogen-generating naphthalenes in said feedstock, by recycling a proportion of said gaseous fraction to the base of said distillation column and recycling a proportion of said desulphurized fraction to said distillation column, the proportion of each depending upon the desired boiling range of said overhead product and the naphthalene deficiency in said feedstock; and, recovering said desulphurized fraction as a desired product.

2. The process of claim 1 including the step of removing hydrogen sulphide from said gaseous fraction before recycling.

3. The process of claim 1 in which each said proportion is recycled to the base of said column.

4. The process of claim 1 including the steps of

separating a number of desulphurized fractions from the products of the autofining zone; recycling a proportion of the lighter of said desulphurized fractions to said distillation column; and, recovering the remainder of said desulphurized fractions as desired products.

5. The process of claim 1 in which the feedstock is a debutanized crude oil, including the steps of: separating a number of desulphurized fractions from the products of the autofining zone; recycling the lighter of said fractions to the top of said primary distillation column as reflux and recycling a proportion of the other desulphurized fractions to the base of said column in admixture with the proportion of said gaseous fraction being recycled to said base; and, recovering the remainder of said desulphurized fractions as desired products.

6. The process of claim 4 in which said proportion of said lighter fraction is recycled to the base of said primary distillation column.

7. The process of claim 4 in which said proportion of said lighter fraction is recycled to the top of said primary distillation column as reflux.

8. The process of claim 4 in which the feedstock is an asphaltic crude oil, including the steps of de-asphalting the crude oil; and, passing the de-asphaltered crude oil to said primary distillation column.

9. The process of claim 4 in which the feedstock is an asphaltic crude oil including the steps of: contacting the crude oil with asphalt precipitants selected from the class consisting of dissolved hydrogen, methane, ethane, propane and butane under a pressure of up to 100 lb./sq. in. and a temperature between 0° F. and 200° F., and then passing the vaporized de-asphaltered crude oil obtained to said primary distillation column.

10. The process of claim 4 in which the feedstock is an asphaltic crude oil including the steps of: contacting the crude oil with asphalt precipitants selected from the class consisting of methane, ethane, propane and butane; separating the de-asphaltered mixture into a wax phase and an oil phase; and, passing one of said phases to said primary distillation column in admixture with the hydrogen and light hydrocarbons being recycled thereto.

11. The process of claim 5 in which said proportion of the other desulphurized fractions is recycled to said column in admixture with the debutanized crude oil supplied thereto.

12. The process of claim 7 in which the feedstock is crude oil, including the steps of: debutanizing the crude oil; vaporizing the debutanized crude oil; and, passing the vapor to said primary distillation column.
